UNITED STATES PATENT OFFICE.

JOHN HASZINGER, OF VICKSBURG, MISSISSIPPI.

SHOE.

SPECIFICATION forming part of Letters Patent No. 267,887, dated November 21, 1882.

Application filed August 17, 1882. (No model.)

To all whom it may concern:

Be it known that I, JOHN HASZINGER, of Vicksburg, in the county of Warren and State of Mississippi, have invented a new and useful 5 Improvement in Shoes, of which the following is a full, clear, and exact description, reference being had to the annexed drawings, forming part of this specification.

My invention relates to an improvement in 10 that form of shoe which is constructed without side seams; and the invention consists of an upper having the tongue so formed as to provide edges for attaching tie-straps, the object being to provide a so-called "seamless shoe" 15 which shall be strongly supported at the instep, and which, for such a shoe, shall be formed at a minimum of expense in actual cutting and stitching, without at the same time involving greater expense of stock than is ordinarily required for a seamless shoe.

In the drawings, Figure 1 is a side elevation of the shoe, and Fig. 2 is a blank from which the upper is formed.

The upper A, which is made in a single piece, 25 has slots *a a*, of angular shape, cut in its sides from the center, and extending obliquely downward to form the tongue *b*, and to provide a curved edge, *c*, to which the instep-strap *d* is to be sewed. With this construction the straps 30 may be made of heavier and stronger leather than the body of the upper, as is needed, and they may also be made of suitable length for buckles, if desired. Not only a perfect and easy fit, but durability and economy in cutting are thus secured.

I am aware that tie-straps or buckle-straps

have before been formed of separate pieces sewed to the parts forming the upper of a shoe; but such straps have been used in such manner as to secure different objects from those 40 aimed at by me. For instance, the tie-strap has formed an integral part of the upper, being sewed between the vamp and the quarters; but this construction requires two seams at the side, whereas I desire to dispense with such 45 side seams altogether. Again, a tie-strap has been secured to the quarters of a shoe to serve as a heel-lifter and to re-enforce the side elastics. This construction, however, is only adapted to 50 gaiters in which the uppers are formed of two or more pieces. In my invention, on the contrary, the upper may be formed of a single piece, and scraps of leather may be utilized in forming the tie-straps, which are sewed to the lower edge of slots cut in the vamp to form the 55 tongue, and in such manner that they shall completely cover the slots when tied across the instep.

Having thus described my invention, what I claim, and desire to secure by Letters Patent, 60 is—

The shoe-upper having the angular slots *a a* cut through its sides and extending obliquely downward to form the tongue *b*, and having the straps *d d* sewed to the outer edges, *c c*, of 65 the slots, and adapted to cover the said slots when tied across the tongue, substantially as and for the purposes specified.

JOHN HASZINGER.
